UNITED STATES PATENT OFFICE.

FRANK N. SAMSON, OF ELGIN, ILLINOIS.

COMBINED REAMING AND FACING MECHANISM.

Application filed February 16, 1923. Serial No. 619,362.

My invention relates to an improvement in a machine for reaming and facing the bushings of steering spindles of motor vehicles and has among its objects the production of a device of the kind described, which is simple, convenient, compact, durable, reliable, efficient and satisfactory for use wherever found applicable.

Another object of my invention is to provide means for manually feeding the spindle against the ends of the cutting tools and provide stop means automatically operable to limit said feeding movement when the distance between the spindle bushings is of the proper predetermined amount.

Another object of my invention is to provide means for reaming the bores and facing the ends of the bushings in unison.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts:

Fig. 1 is a side elevation of my device;

Fig. 2 is an end elevation thereof;

Fig. 3 is a section taken substantially on line 3—3 of Fig. 1;

Fig. 4 is a section taken substantially on line 4—4 of Fig. 3, and

Fig. 5 is a section taken substantially on line 5—5 of Fig. 2.

In the drawings, wherein I have illustrated the preferred embodiments of my invention, 1 indicates a frame-work for supporting the various parts of the mechanism, said frame-work being of any suitable size, shape and material, and preferably having uprights 2—2 at one end integral with the frame and provided with aligned bores therethrough. A movable upright member 3 is carried at the other end of the frame 1, said part 3 being adjustable longitudinally of the part 1 and in the form shown has a tongue 4 engaging in a groove or slot 5 in

said part. The tongue and slot engagement permits of longitudinal adjustment but prevents any side or lateral play between the parts. One or more screws or bolts 6 may be positioned between the parts 1 and 3 to lock the parts together in their adjusted positions. In order to provide for further adjustment elongated apertures 7 have been provided in the base of the part 3 and through which apertures the bolts 6 extend.

A bar or rod member 8 is positioned through the aligned parts 2—2 and has a thread 9 formed thereon, one end of the member 8 having an axial recess 10 therein. In order to prevent the rotational movement of the rod 8, a key 11 may be interposed between the part 2 and the rod, said key engageable in a longitudinal slot or key-way in said rod, or any other means may be provided for the purpose.

A hand-wheel 12 having a threaded bore therethrough is mounted upon the rod 8 to engage the external threads 9 thereof so that when the hand-wheel is rotated the rod 8 will be moved in one direction or the other, dependent upon the rotational direction of the hand-wheel.

In order to adjustably limit the longitudinal movement of the rod 8, for a purpose to be more clearly hereinafter described, a collar 13 may be provided thereon and adapted to abut against the end wall of the bore of the member 2 through which the rod extends. A set screw, or any other equivalent means, 14 may be employed to adjustably lock the collar in place.

A hollow facing tool 15, having cutting teeth 16 at one end, is positioned in the bore through the member 3 and is rotatable therein. A reamer 17 is adapted to be inserted through the bore of the facing tool and held in place to prevent relative rotational movement therebetween so that when the facing tool is rotated the reamer will be rotated simultaneously therewith. The outer end of the facing tool is preferably connected to an internal toothed gear 18 which is adapted to be driven by a pinion 19 actuated by a crank or handle 20, as shown, or if it is desired to dispense with gearing the handle 20 may be connected directly to the

outer end of the facing tool. Likewise the machine may be power driven if so desired.

A centering pin 21, having a reduced neck portion 22, is slidable within the axial recess 10 of the member 8 and is resiliently pressed outwardly by a spring 23 interposed between the centering pin and the base of the recess. A set screw 24 is inserted radially of the member 8 to engage in the reduced neck portion 22 and limit the movement of the pin axially of the recess.

The method generally employed for reaming and facing the bushings at the opposite ends of the steering knuckle of a motor vehicle is to first ream and face one bushing, then take the bushing to the motor vehicle and place it in position in the axle to determine how much the opposite bushing should be faced, then replace the knuckle in the reaming machine and ream the other end and face it. The knuckle is then taken to the axle and tried and generally it must be taken back to the machine and faced a bit more, or perhaps it has been faced too much, thereby necessitating the inserting of new bushing and a refacing and reaming, or if the bushing is left in place the resultant fit in the axle will not be a perfect one. It is also quite likely that the axes of the two bushings will not be in perfect alignment.

With my improved device, however, the steering knuckle 25, having the removable bushings 26 at its opposite ends, is placed in the position shown in the drawings, and by advancing the part 8 while the facing tool and reamer are rotated one bushing of the knuckle will be simultaneously reamed and faced. It will be noted that in the improved type of centering pin used, there will be no pressure on the inside of the bushing, caused by the centering pin, the centering pin serving only for the purpose of centering, and for nothing else, and permitting the end of the steering knuckle, or rather the end of the bushing therein to abut against the end of the movable member 8. After one bushing has been reamed and faced, the knuckle is reversed and recentered in the device and the opposite bushing reamed and faced, the operator continuing the feeding movement of the knuckle by turning the hand-wheel 12 until the stop member 13 abuts squarely against the end of the outer side of the upright 2. This automatically acts as a gauge and insures that the distance between the teeth of the facing tool and the end of the member 8 is of the required predetermined amount, this amount having been previously set for the exact distance between the opposite faces of the axle yoke.

Thus it is seen that the distance between the outer ends of the bushings are automatically gauged and there is no fit-and-try method of operation. The adjustments be-

tween the frame 1 and the part 3 permits of a great range of sizes between which the gauging may be done.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a machine adapted to ream and face the bushings assembled in steering spindles, the combination with a base, and spaced uprights mounted on the base, of a combined reaming and facing tool rotatably carried by one of said uprights, a bar loosely carried by the other of said uprights, means carried by said bar for supporting one end of a steering knuckle while the other end is supported by the reaming portion of the aforesaid combined tool, means for moving the bar toward the tool carrying upright to feed the steering spindle axially of the combined tool so that the bushing being worked upon first will be reamed and then faced, and means for gauging the distance of movement of the steering spindle with respect to the facing portion of the combined tool, whereby steering spindles of uniform overall length will be produced.

2. In a machine adapted to ream and face the bushings assembled in steering spindles, the combination with a base, and head and tail stocks mounted on the base, of a combined reaming and facing tool rotatably carried by the head stock, a horizontal bar loosely carried by the tail stock, a center carried by the said bar to support one end of a steering spindle while the other end of said spindle is supported by the reaming portion of the aforesaid combined tool, means for moving the bar toward the head stock to feed the steering spindle axially of the combined tool so that the bushing being worked upon first will be reamed and then faced, and means carried by the bar for gauging the distance of movement of the steering spindle with respect to the face portion of the combined tool, whereby steering spindles of uniform overall length will be produced.

3. In a machine adapted to ream and face the bushings assembled in steering spindles, the combination with a base, and spaced uprights mounted on the base, of a combined reaming and facing tool rotatably carried by one of said uprights, a bar loosely carried by the other of said uprights, means carried by said bar for supporting one end of a steering spindle while the reaming portion of the aforesaid tool supports the other end of said spindle, means for moving the

bar toward the tool carrying upright to feed the steering spindle axially of the combined tool so that the bushing being worked upon first will be reamed and then faced, and a collar adjustably mounted on the bar and engageable with a portion of the adjacent upright to gauge the distance of movement

of the steering spindle with respect to the facing portion of the combined tool, whereby steering spindles of uniform overall 10 length will be produced.

In testimony whereof, I have hereunto signed my name.

FRANK N. SAMSON.
